UNITED STATES PATENT OFFICE.

WILLIAM M. THOMAS, OF GRAND RAPIDS, MICHIGAN, ASSIGNOR OF ONE-HALF TO THE GRAND RAPIDS ELECTRIC LIGHT AND POWER COMPANY, OF SAME PLACE.

CUT-OUT FOR ELECTRIC LAMPS.

SPECIFICATION forming part of Letters Patent No. 312,529, dated February 17, 1885.

Application filed April 17, 1884. (No model.)

To all whom it may concern:

Be it known that I, WILLIAM M. THOMAS, of Grand Rapids, in the county of Kent and State of Michigan, have invented certain new and useful Improvements in Automatic Switches for Electric Lights, of which the following is a specification.

When electric lamps are connected in series, they are usually provided with some automatic devices for feeding the carbon and maintaining the arc interval between the electrodes. This automatic adjustment, however, may in some cases fail to properly act, and the carbons in burning away may produce an excess of arc length, which would not only monopolize electric energy at that point in the circuit, but the excessive length of the arc would be more or less destructive to the lamps, and might endanger the surroundings. The breaking of the carbon also sometimes produces a rupture in the lamp sufficient to open the circuit.

The object of my invention is to provide an automatic cut-out for an arc lamp, the carbon points or electrodes of which are automatically adjusted. The current is shunted from the lamp by the cut-out when its path through the lamp is destroyed by the rupture of the electrodes, or when the length of the arc between the electrodes is abnormally increased. Serious interruptions or breaks in the current of the main conductor are thereby prevented.

The organization and circuit-connections of my improved cut-out are illustrated in the accompanying drawing, which is a diagram view showing the essential features of the invention.

The main circuit is indicated by the full line L, in which the current flows in the direction indicated by the arrow to the + carbon of the lamp. The line from the opposite or - carbon is indicated by dotted lines, the direction of the current still being shown by the arrow.

The two sections of the line which approach and leave the lamp are wound parallel and in the same direction around a soft-iron core, A, as clearly shown in the drawing. The usual shunt or branch circuit, s, containing a coil, R, of relatively high resistance, is thrown

around the electrodes of the lamp, starting at 50 the conductor indicated by the full line before it enters the + carbon, and connecting with the line indicated by dotted lines at some suitable point after it leaves the core A. Under this condition of the circuit and connections, upon the failure or interruption of the circuit at the electrodes of the lamp, the continuity of the circuit will be maintained through the shunt s, and the cut-out will instantaneously be operated to effectually shunt 60 the current from the lamp, as follows: A suitable armature, B, is arranged opposite the end of the soft-iron core A. This armature is carried upon a spring, C, which is mounted on a suitable support, and may be provided 65 with any ordinary adjusting devices. The spring C and armature B are electrically connected with the circuit indicated by the full line at the point x, while the core A is connected with the circuit indicated by the dotted line at the point y. It is obvious, therefore, that when the armature is drawn into contact with the magnet A a supplementary shunt passing from x through C B A and the line l will be completed around the electrodes 75 of the lamp. This shunt is thrown into operation in the following manner: As the two branches of the main line L are wound parallel and in the same direction on the core A, and as the current passes in opposite directions through them, the effect is that they neutralize each other more or less. The spring C may be adjusted, however, so that when the resistance between the electrodes caused either by the increase in the length of the arc or the 80 rupture of the circuit is so great that electromotive force in the dotted line running around the core A is reduced to a given amount, the excess of current in that part of the circuit indicated by the full line will energize the core 85 A with such a power that the armature B will be attracted, and the supplementary shunt above described will be completed. The amount of current diverted from the dotted line which surrounds the core through the shunt s will 90 be, generally speaking, proportional to the length of the arc. It is obvious, therefore, that by adjusting the armature B the device 95

may be made to cut out whenever the arc exceeds any given limit in length.

A suitable resistance, R_h , which may be adjustable, may be placed in the line l . Should the 5 carbon points, therefore, be brought together after a rupture, or after the lamp has been cut out, a sufficient amount of the current would pass through the electrodes of the lamp to overcome or neutralize the magnetic energy of the 10 core A. The armature B would therefore be drawn back out of contact with the core A, thus opening the shunt-circuit and permitting the normal passage of the current through the main circuit, as before described, thereby causing 15 the automatic relighting of the lamp.

I have represented my improved devices in diagrammatic form; but the construction and operation will of course be clear to any one familiar with the subject of electricity; and it 20 is obvious that the construction may be varied without departing from the principle of the invention.

I am aware that it has heretofore been proposed to organize electric lamps with the carbons in a branch of the main line, and shunted by high and low resistance shunts, for the purpose of regulating the light and controlling the movement of the carbon—such as shown, for instance, in the patent of Bain, No. 300,433, 30 dated June 17, 1884. I do not, therefore, claim such subject-matter, but limit myself to the peculiar characteristics of my invention set forth in the claims.

I claim as my invention—

35 1. The combination, substantially as set forth, of a main line, the carbons of an electric lamp placed in a loop of the main line, an electro-magnet or core which is wound with both legs or branches of the loop in which 40 the lamp is placed, an armature for said mag-

net, and a shunt-circuit which is automatically completed by the attraction of said armature when the arc length or resistance in the lamp exceeds a certain limit.

2. The combination, substantially as set forth, of a main line, the carbons of an electric lamp placed in a loop of the main line, an electro-magnet or core which is wound with both legs or branches of the loop in which the lamp is placed, an armature for said magnet, a shunt-circuit which is completed by the attraction of said armature, a suitable resistance in said shunt-circuit, and a second ordinary shunt-circuit of relatively high resistance, for the purpose set forth. 50 55

3. The combination, substantially as set forth, of a main line, the carbons of an electric lamp placed in a loop of the main line, an electro-magnet or core which is wound with both legs or branches of the loop, an armature for said magnet, a shunt-circuit which is completed by the attraction of said armature, and a resistance in said shunt-circuit. 60

4. The combination, substantially as set forth, of a main line, the carbons of an electric lamp placed in a loop of the main line, a shunt around the lamp, electro-magnetic cut-out devices included in both legs of the main line loop for completing the shunt when 70 the arc length or resistance of the lamp has been abnormally increased, and means for adjusting the cut-out devices to act at a given length of arc in the lamp. 75

In testimony whereof I have hereunto subscribed my name.

WILLIAM M. THOMAS.
